UNITED STATES PATENT OFFICE.

JACOB L. MOORE, OF MUNCIE, INDIANA, ASSIGNOR OF ONE-HALF TO JOHN F. BANTA,
OF GOSHEN, INDIANA.

BEDSTEAD.

1,318,222.

Specification of Letters Patent.

Patented Oct. 7, 1919.

Application filed April 13, 1918. Serial No. 228,412.

To all whom it may concern:

Be it known that I, JACOB L. MOORE, a citizen of the United States, residing at Muncie, in the county of Delaware and State 5 of Indiana, have invented a certain new and useful Improvement in Bedsteads, of which the following is a full, clear, concise, and exact description.

My invention relates to bed-steeds or bed-frames which employ side rails of angle iron formation that are united at their ends with the corner posts of the bed-stead which may be of wood or metal. The invention has for its object the provision of improved 15 means for effecting union between the bed posts and the ends of the side rails.

My invention resides in the corner post of a bed having a rail supporting lug or lugs projecting toward the adjacent end of 20 a side rail of the bed, in combination with a coupling member engageable with said lug or lugs and carried by this adjacent end of the side rail, this coupling member itself being also formed of angle iron and of 25 such shape as to have very rigid union with said side rail end to which it is attached. In forming this coupling member I employ a blank of angle iron and cut from it a section of suitable length. The coupling member which is formed from this angle iron is 30 disposed at right angles to the rail which carries it. In one wall of the angle iron section I form a recess or recesses corresponding in number to the number of lugs 35 upon the adjacent post, these recesses being preferably in the nature of oblong holes completely surrounded by the metal of the angle iron. The other wall of the angle iron section is so cut away and notched as to 40 have a part adapted to overlie the horizontal wall of the angle iron rail carrying it and another part which is adapted to underlie this wall of the angle iron rail and which latter part is riveted or bolted against the 45 inner face of the upright wall of said angle iron rail. The parts of the coupling member between which the horizontal wall of the rail is thus disposed have snug fit with this wall to prevent turning movement of the 50 post with respect to the rail in the vertical plane of the rail.

I will explain my invention more fully by reference to the accompanying drawing showing the preferred embodiment thereof 55 and in which Figure 1 is a perspective view

illustrating the invention, this figure showing a portion of the bed post and a portion of a side rail assembled therewith in accordance with the invention; Fig. 2 is a side view of the structure appearing in Fig. 1 taken from the outside of the bed; Fig. 3 is a side view of the structure appearing in Fig. 1 taken from the inside of the bed structure; Fig. 4 is a sectional view on line 4—4 of Fig. 3; Fig. 5 is a front view 65 of the coupling member separated from all associated parts; and Fig. 6 illustrates the coupling member in conjunction with an angle iron out of which it has been formed.

Like parts are indicated by similar characters of reference throughout the different figures.

Each of the four posts 1 of the bed-stead or bed-frame may be of wood or metal. The lugs 2, by means of which each of the two 75 angle iron side rails 3 are to be assembled with the corner posts, may be supported upon these posts in any suitable way. As illustrated, these lugs 2 are in the nature of outwardly projected hooks which are struck 80 from the plate 4, this plate being secured to the corresponding post by means of the screws 5. However, I do not wish to be limited to the employment of such a plate as it is obvious that the hooks or lugs may 85 be directly secured to the post if desired without the intermediation of the plate. The coupling member attached to each end of each side rail 3 is desirably formed as illustrated most clearly in Fig. 6 which shows 90 the employment of a portion of angle iron out of which the coupling member may readily be made.

One wall 6 of the angle iron coupling member is to have flat contact with the plate 95 4 or is to engage the post directly if such plate is absent. This wall 6 has two lug receiving openings 7, in the embodiment of the invention illustrated, inasmuch as I have shown two sets of lugs 2 upon the illustrated 100 post 1, these sets being separated longitudinally of the post. It is obvious that the invention is not to be limited to the number of lugs or sets of lugs and the number of openings 7 in said coupling member.

The other wall of the coupling member is formed with a notch 8 extending transversely of the coupling member to receive the horizontal wall of the corresponding side rail whereby the coupling member is 110

disposed at right angles to said side rail. The portion 9 which overlies the notch has snug engagement with the upper face of the horizontal wall of the side rail while the portion 10 projects inwardly from the portion 9 and has snug engagement with the bottom face of said horizontal wall of the side rail. The notch 8 is desirably enlarged or depressed at its inner end upon one side 10 of the horizontal wall of the side rail as indicated at 11 to lessen the work of the tools that are employed in making the coupling member and also to facilitate the insertion of the adjacent rail end into the notch, it 15 being possible to incline the coupling member with respect to the rail end in the process of assembly.

Holes 12 are formed in the part 10 of the coupling member to receive the shanks of 20 rivets 13 which are employed to effect firm engagement between the part 10 of the coupling member and the upright wall of the side rail, said part 10 being beneath the horizontal wall of the side rail and in engagement with the inner face of the upright wall of the side rail. The parts 9 and 10 of 25 the coupling member are preferably in the same plane and parallel with the upright wall of the side rail or, more generally speaking, are upon the inner side of the 30 general plane of the upright wall of the side rail whereby both of these parts of the coupling member are in engagement with the horizontal wall of the side rail and co-operate with this horizontal wall to resist 35 turning movement of the side rail upon the coupling member.

When the angle iron side rails are disposed with their horizontal walls above their 40 upright walls, the side rails are adapted to support wire mattress structures directly. By means of the embodiment of the invention illustrated the coupling members may be reversed in position to bring the horizontal 45 walls of the side rails lowermost, in which reversed arrangement these horizontal side walls of the side rails may readily support the ordinary wooden bed slats.

The notch 8 desirably terminates flush 50 with the inner face of that wall 6 of the coupling member which engages the lugs and the end of the side rail desirably abuts against such face of this wall 6 to secure more rigid relation between the post and 55 rail. Inasmuch as the bottom edge of the portion 9 and the top edge of the portion 10 are separated a distance just about equal to the thickness of the horizontal wall of the side rail, the portion 9 is caused to terminate 60 over the inner enlarged part of the notch 8 in order to form an enlarged gap into which the end of the side rail may be inserted while the rail and the rail coupling member are tilted with respect to each other to make it 65 easy to assemble these elements preparatory

to passing the rivets 13 therethrough. Owing to the engagement of the portion 10 with the inner faces of the two walls of the side rails, the engagement of the portion 9 with the outer face of the horizontal wall of 70 the side rail, and the abutment of the adjacent end of the side rail against the wall 6 of the coupling member, a very rigid and firm union between the side rail and the coupling member is effected which union is 75 of such a nature as to prevent the tilting of said side rail with respect to the coupling member when the head and foot pieces or boards of the bedstead are united by the side rails.

The invention is not to be limited to the reversability of the side rails not to the details of construction illustrated.

Having thus described my invention I claim as new and desire to secure by Letters Patent the following:

1. In a bedstead, the combination with a bedstead corner post; of a side rail supporting lug carried by the post; an angle iron side rail having one wall horizontal and the other wall upright; and a coupling member formed of angle iron and having one wall adapted for engagement with said lug and the other wall provided with a notch terminating at the first wall of the coupling member and extending transversely of the coupling member and separating this wall of the coupling member into two portions between which the horizontal wall of said side rail is snugly received, one of said portions being secured to the upright wall of the side rail and against the inner face of this upright wall, and both of said portions of the coupling member being upon the inner side of the general plane of the upright wall of the side rail, the inner end of the notch in the coupling member being enlarged on one side of the horizontal wall of the side rail, the portion of the coupling member on the other side of said horizontal wall terminating over the enlarged portion of the notch to facilitate the assembly of the side rail and coupling member.

2. In a bedstead, the combination with a bedstead corner post; of a side rail supporting lug carried by the post; an angle iron side rail having one wall horizontal and the other wall upright; and a coupling member formed of angle iron and having one wall adapted for engagement with said lug and the other wall provided with a notch extending transversely of the coupling member and separating this wall of the coupling member into two portions between which the horizontal wall of said side rail is snugly received, one of said portions being secured to the upright wall of the side rail and against the inner face of this upright wall, and both of said portions of the coupling member being upon the inner side of the

general plane of the upright wall of the side rail, the inner end of the notch in the coupling member being enlarged on one side of the horizontal wall of the side rail, the portion of the coupling member on the other side of said horizontal wall terminating over the enlarged portion of the notch to facilitate the assembly of the side rail and coupling member.

5 3. In a bed-stead, the combination with a bed-stead corner post; of a side rail supporting lug carried by the post; an angle iron side rail having one wall horizontal and the other wall upright; and a coupling member formed of angle iron and having one wall adapted for engagement with said lug and the other wall provided with a notch terminating at the first wall of the coupling member and extending transversely of the coupling member and separating this wall of the coupling member into two portions between which the horizontal wall of said side rail is snugly received, one of said portions being secured to the upright wall of the side rail and against the inner face of this upright wall, the inner end of the notch in the coupling member being enlarged on one side of the horizontal wall of the side rail, the portion of the coupling member on the other side of said horizontal wall terminat-

ing over the enlarged portion of the notch to facilitate the assembly of the side rail and coupling member.

4. In a bed-stead, the combination with a bed-stead corner post; of a side rail supporting lug carried by the post; an angle iron side rail having one wall horizontal and the other wall upright; and a coupling member formed of angle iron and having one wall adapted for engagement with said lug and the other wall provided with a notch extending transversely of the coupling member and separating this wall of the coupling member into two portions between which the horizontal wall of said side rail is snugly received, one of said portions being secured to the upright wall of the side rail and against the inner face of this upright wall, the inner end of the notch in the coupling member being enlarged on one side of the horizontal wall of the side rail, the portion of the coupling member on the other side of said horizontal wall terminating over the enlarged portion of the notch to facilitate the assembly of the side rail and coupling member.

In witness whereof, I hereunto subscribe my name this 3rd day of April, A. D. 1918.

JACOB L. MOORE.
